UNITED STATES PATENT OFFICE.

CHARLES HUGH DUFFY, OF CHEVY CHASE, MARYLAND.

SPARK-PLUG.

1,301,824.

Specification of Letters Patent. Patented Apr. 29, 1919.

Application filed April 16, 1918. Serial No. 228,935.

To all whom it may concern:

Be it known that I, CHARLES HUGH DUFFY, a citizen of the United States, residing at Chevy Chase, in the county of Montgomery and State of Maryland, have invented certain new and useful Improvements in Spark-Plugs, and do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to spark-plugs for internal combustion engines, and has for its object to provide improvements in the method of and construction for seating a 20 slightly tapered insulating core within a complementally slightly tapered spark-plug shell.

The term "slightly tapered" appearing in this specification has reference to a taper 25 which produces or provides what is known as a "sticking taper," the same being a taper which "sticks" or "seizes" when placed with in a complemental taper even to such an extent that no further or additional holding 30 or retaining means or medium is necessary to hold the tapered members in close or tight engagement both against casual displacement or relative rotation.

In that type of spark-plugs, as for example that disclosed in U. S. patent to Davis & Mellen, No. 690,640 patented Jan. 7th, 1902, in which a slightly tapered insulating core is seated in a complementally tapered shell, a perfectly gas tight joint or union can only 40 be obtained by grinding or lapping the complemental tapers of the core and shell.

This invention has for its object to provide a metal band over the slightly tapered portion of the insulating core, and between 45 the core and the complementally tapered portion of the shell; said metal band being preferably formed on and integral with the core-retaining gland.

The invention consists in the arrangement 50 of the parts and in the method of spinning a metal band around the insulating core and between the complementally tapered portion thereof and the shell, in such manner that a close conformation between the parts is assured, and a consequent gas-tight joint is 55 effected, as will be first fully described and

afterward specifically pointed out in the appended claims.

Referring to the accompanying drawing: Figure 1, is a vertical sectional view, of a 60 spark-plug constructed in accordance with this invention, the insulating core being shown in elevation.

Fig. 2, is a similar view, inverted, illustrating the manner of assembling the parts. 65

Fig. 3, is an elevation of the gland, insulation and central electrode after being assembled.

Fig. 4, is an elevation of the gland before being assembled in the shell, and Fig. 5, is a 70 vertical sectional view showing the gland, shell, insulation and central electrode in an assembled position.

Like numerals of reference indicate the same parts throughout the several figures, 75 in which:

1, indicates a spark-plug constructed in accordance with this invention. 2, indicates the insulating core, 3 the shell and 4, the thimble-gland. The core 2, is provided with 80 a shoulder 5, a central enlarged portion 6, a slightly tapered portion 7, and a reduced lower portion 8. 9 indicates the central electrode, the sparking end 10 of which, in the type shown in the drawing, is of disk 85 formation, the periphery of which is spaced away from the shell 3, to form an annular spark-gap 11.

The shell 3 is internally threaded at 12, and externally threaded at 13, for connection with a motor. Within the shell 3, and below the threaded portion 12, is a slightly tapered portion 14 complemental to the slightly tapered portion 7 of the core 2.

The gland 4 is bored to receive the core 2, 95 and includes a threaded portion 15, having an internal annular shoulder 16, and a thin depending tubular portion 17, which encompasses the slightly tapered portion 7 of the core 2, when the said core is initially inserted within the gland 4.

Having thus fully described the several parts of the spark-plug, the method of assembling the parts is as follows:

The assembly is facilitated by inverting 105 the parts, as shown in Fig. 2. The core 2, is inserted in the gland 4, and the shell 3, is placed on the gland, and threaded thereon by rotation, so as to progress the shell 3 with relation to the gland 4. The end of 110 the tubular portion 17 of the gland 4, enters the slightly tapered portion 14 of the shell

3, engaging the beginning of the tapered annular wall of said slightly tapered portion. As the shell 3, is rotated down on the gland 4, the slightly tapered portion 14 of the shell 5 3, gradually spins the tubular portion 17 of the gland 4, inwardly and around the complementally tapered portion of the core 2, and at the same time, said tubular portion 17 is caused to conform closely to the 10 tapered portion 14 of the shell 3, so that when the tapered portion 7 of the core 2 reaches its limit of progress within the tapered portion 14 of the shell 3, the spun portion 17 has formed a closely conforming 15 band around the said tapered portion 7 of the core 2, and between said tapered portion 7, and the complementally tapered portion 14 of the shell 3.

It will be understood that during this 20 spinning operation, the core 2, is being rotated by and with the gland 4, so that there is no relative rotation between the core 2, and the tubular portion 17, which is being spun on and around the tapered portion 7 of the core 2; consequently the spun portion or band 17 grips the tapered portion 7 of the core in a manner which is most effective 25 to produce a gas-tight union between the tapered portion 7 of the core and the spun portion or band 17. It will also be understood that during this spinning operation, the tubular portion 17, which is being spun around and on the tapered portion 7 of the core 2, is rotating on the complementally 30 tapered portion 14 of the shell 3, and grinding a gas-tight joint, so that the most effective conformation is effected between the spun portion or band 17, and the complementally tapered portion 14 of the shell 3.

40 As distinguishing this construction and method from the prior art, it is to be understood that in spinning and disposing the metal band 17 between the complemental tapers 14 and 7, a sticking action is effected 45 between the taper 7 and the band 17 and between the band 17 and the taper 14, in such manner that an air-tight union or joint between these elements does not depend wholly upon the pressure maintained by the 50 threaded portion 15 of the gland 4. In this instance the principal function of the threaded connection between the gland 4 and shell 3 is to rotate the band portion 17 and insulating core with relation to the shell 55 3, and to spin the band portion between the complemental tapers 7 and 14 and to progress the band portion 17 and taper 7 into the complemental taper 14 until a "sticking" action is effected. This function is accomplished 60 by relatively slight pressure of the gland 4 longitudinally of the insulating core, while after the complemental tapers are positioned, the "sticking" character of the tapers 7 and 14 relieves the threads of 65 the gland 4 from holding the insulating core

against the full explosive force in the motor. As a matter of fact the insulating core is effectively held in position by a transverse gripping of the complemental tapers rather than by pressure applied longitudinally of 70 the insulating core in the direction of the shell.

By means of this construction and method, a perfectly tight seating of the core is effected, while the core 2, and gland 4 are 75 readily demountable from the shell 3, as a unit, and upon reassembly, the initial conformation of the parts is assured.

What I claim as new and desire to secure by Letters Patent of the United States, is: 80

1. A spark-plug of the type in which the insulating core and the metal shell are provided with slightly tapered portions complemental to each other, an insulating core having a sticking taper, a metal shell having 85 a sticking taper complemental to the sticking taper of the insulating core, and a metal band closely encompassing the sticking taper of the insulating core, said plug including 90 means providing for rotation of said insulating core and metal band with relation to the shell to progress the insulating core and metal band inwardly of the shell, said metal band and closely conforming to the complemental sticking taper in the metal shell. 95

2. A spark-plug of the type in which the insulating core and the metal shell are provided with slightly tapered portions complemental to each other, an insulating core having a sticking taper, a metal shell having 100 a sticking taper complemental to the sticking taper of the insulating core, and a thin readily distortable metal band closely encompassing the sticking taper of the insulating core, said plug including means providing for rotation of said insulating core and metal band with relation to the shell to 105 progress the insulating core and metal band inwardly of the shell, said metal band and closely conforming to the complemental sticking taper in the metal shell. 110

3. A spark-plug including an insulating core provided with a sticking taper intermediate its ends, a metal shell to receive the insulating core, the shell being provided 115 with a sticking taper complemental to the sticking taper on the insulating core, and a metal band rotatable with the insulating core within the shell and spun on and around the sticking taper of the insulating core 120 and disposed between the same and the complemental sticking taper in the metal shell.

4. A spark-plug including a metal shell provided with an internal sticking taper, a core-retaining gland for connection with said shell, an insulating core within said gland, the core being provided with a sticking taper complemental to the sticking taper in the shell, the said gland being provided with a readily distortable tubular depending 125 130

portion spun on and around the sticking taper of the insulating core to form a band thereon, and closely conforming to the sticking taper in the shell.

- 5 5. A spark-plug including a metal shell threaded for connection with a motor and having an internal bore which includes a sticking taper, an insulating core and a suitable electrode, a gland for connection with 70
10 said shell, a tubular portion on said gland and an internal shoulder therein, a sticking taper on said insulating core complementary to the sticking taper in the shell, said tubular portion on the gland being adapted to 75
15 receive the sticking taper of the insulating core, the said tubular portion being adapted to engage the said sticking taper in the shell to spin said tubular portion on and around the sticking taper of the insulating core and 80
20 between the same and the complementary sticking taper in the shell.

6. A spark-plug including a metal shell having a bore therein which includes a sticking taper, an insulating core having an enlarged central portion forming an upper shoulder and a sticking taper complementary to the sticking taper in the shell, a gland for connection with said shell and having an internal shoulder complementary to the shoulder 90
25 on the insulating core and having a tubular portion to receive the sticking taper of the insulating core, said tubular portion being adapted to engage the sticking taper in the shell to spin the tubular portion on and 95
30 around the sticking taper of the insulating core and between the same and the sticking taper in the shell complementary to the sticking taper of the insulating core.

7. A spark-plug comprising a metal shell 100
40 having a sticking taper therein, an insulating core having an enlarged portion thereon forming an upper shoulder and a sticking taper complementary to the sticking taper in the shell, a gland having a shoulder therein complementary to the shoulder on the insulating core and having a tubular portion to receive the sticking taper of the insulating core, said tubular portion being adapted to engage and rotate on the sticking taper in 105
45 the shell to spin said tubular portion on and around the sticking taper of the insulating core and to grind a gas-tight joint between the spun tubular portion and the sticking taper in the shell.

- 55 8. A spark-plug including a metal shell having a sticking taper therein, a gland for connection with said shell, an insulating core to be received by said gland, a tubular portion on said gland adapted to engage the sticking taper in the shell and to rotate thereon to spin the tubular portion on and around said insulating core.

9. A spark-plug including a shell having a sticking taper therein, an insulating core 120
65 having an enlarged portion forming an up-

per shoulder and a lower sticking taper complementary to the sticking taper in the shell, a gland for connection with the shell and provided with an internal shoulder complementary to the said shoulder on the insulating 70
core and provided with a readily distortable portion, said insulating core being adapted to be received by said gland, the said readily distortable portion on said gland being adapted to engage the sticking taper in the 75
shell and to rotate thereon to spin the readily distortable portion on and around the complementary sticking taper of the insulating core and to grind a gas-tight joint between the sticking taper in the shell and the 80
readily distortable portion of the gland.

10. A spark-plug including a shell, a gland, an insulating core provided with a sticking taper, a readily distortable portion on the gland, said gland being adapted to 85
receive the insulating core, said shell being provided with means therein to be engaged by the readily distortable portion on the gland to distort said readily distortable portion into close engagement with the sticking taper of the insulating core upon inward progression of said gland and core within 90
the shell.

11. The herein described method of seating an insulating core having a sticking 95
taper in a spark-plug shell provided with a complementary sticking taper, which consists in inserting the insulating core within a threaded gland, in threading the gland into the spark-plug shell to rotate the gland 100
against the complementary sticking taper in the spark-plug shell to spin the said gland on and around the sticking taper on the insulating core and between the same and the complementary sticking taper in the spark- 105
plug shell.

12. The herein described method of seating an insulating core having a sticking taper within a spark-plug shell having a complementary sticking taper, which consists in providing a metal band around the sticking taper of the insulating core, and in progressing by rotation the insulating core and metal band inwardly of the spark-plug 110
shell to dispose said metal band against the complementary sticking taper of the spark-plug shell and between the same and the sticking taper of the insulating core.

13. The herein described method of seating an insulating core having a sticking 120
taper within a spark-plug shell having a sticking taper, which consists in inserting a core-retaining gland having a tubular portion and the slightly tapered insulating core within the slightly tapered spark-plug shell, 125
and in rotating the gland against the sticking taper of the spark-plug shell to spin the tubular portion of the gland between the insulating core and the spark-plug shell.

14. The herein described method of seat- 130

ing an insulating core having a sticking taper within a spark-plug shell having a sticking taper, which consists in relatively rotating a threaded core retaining gland within and with relation to a spark-plug shell to relatively progress the core-retaining gland against the complementary sticking taper of the spark-plug shell to spin the core retaining gland between the complementary 10 tapers of the insulating core and the spark-plug shell.

15. The herein described method of seating an insulating core having a sticking taper within a spark-plug shell having a complementary sticking taper, which consists in relatively progressing a threaded core-retaining gland inwardly of a spark-plug shell and against the sticking taper therein to distort the threaded core-retain-

ing gland and spin the same between the complementary tapers of the insulating core and the spark-plug shell.

16. The herein described method of retaining an insulating core having a sticking taper within a spark-plug gland, which consists in relatively progressing a threaded core-retaining gland inwardly of a shell having a sticking taper complementary to the sticking taper of the insulating core to spin the core-retaining gland against the sticking 25 30 taper in the shell and on and around the sticking taper of the insulating core.

In testimony whereof, I affix my signature in presence of two witnesses.

CHARLES HUGH DUFFY.
